COMBINED KNOB AND ESCUTCHEON

Fred J. Russell, 3800 Don Felipe Drive,
Los Angeles, Calif.

Filed Dec. 22, 1958, Ser. No. 53,845

Term of patent 14 years

(Cl. D50—3)

Fig. 1

Fig. 2

Fig. 3

Fig. 4

FIGURE 1 is a front perspective view of a combined knob and escutcheon showing my new design.

FIGURE 2 is a side elevational view.

FIGURE 3 is a front elevational view.

FIGURE 4 is a fragmentary sectional view of the face portion of the knob.

I claim:

The ornamental design for a combined knob and escutcheon, as shown.
